DECK CHAIR

Orval R. Platter, North Vernon, Ind., assignor to
 North Vernon Industries, Inc., North Vernon,
 Ind., a corporation of Indiana

Application June 20, 1934, Serial No. 731,507

3 Claims. (Cl. 155—147)

This invention relates to a deck chair of the folding type, and it has for its object to provide a comfortable chair of pleasing appearance and of simple and yet sturdy construction.

Another object of this invention is to provide a chair of this type wherein features heretofore rendering such chairs uncomfortable are avoided.

Further objects and advantages of the invention will be apparent from the detailed description of a preferred embodiment which follows:

10 In the drawing:

Fig. 1 is a view in perspective of my preferred embodiment; and

Figs. 2 and 3 are detail views.

15 Fig. 4 is a detail of a modified form of seat construction.

Similar reference characters designate corresponding parts in all figures of the drawing.

A backing strip 1 of canvas or the like is stretched between two back rails 2, to which the strip is fastened in any suitable manner. A bracing member 3 connects the opposite ends of said back rails. Legs of cross type are provided comprising legs 5 pivoted respectively to the back rails and legs 4. These legs are pivoted together and spaced by spacer members 7 and are braced at their lower ends by bracing members 6. Arms 8 are pivoted respectively to said back rails and to members 9 which are in turn respectively pivoted to the legs 4. The bracing member 3 is adapted to rest in suitable slots in legs 4.

It will be readily apparent that, with the construction above described, upon removal of the bracing member 3 from legs 4 the members may be folded or collapsed so that they make a flat unit for handling, storing or shipping.

40 A seat for the chair is provided comprising side rails 10 each suitably pivoted at one end to a respective back rail. At the opposite ends the side rails are notched out as shown in detail in Figs. 2 and 3 to mate with correspondingly notched portions on the upper ends of legs 4. A seat proper of canvas or the like is slidably mounted on said side rails preferably by loop sewing or the like.

45 The seat may also be made in the form of an endless belt as shown at 11' in Fig. 4. In either construction it will be readily apparent that when the mating portions of legs 4 and side rails 10 are forced together the seat will be stretched tightly between the side rails at the front edge thereof.

A bracing member 12 is provided adjacent the upper ends of legs 4. By this construction the legs 4 are prevented from collapsing inwardly when weight is transmitted to them from seat 11 through the notched portions of side rails 10.

In constructions heretofore provided the seat material has been fastened to a cross rod extending between the legs and forming the front edge of the seat. Such rods are uncomfortable and tend to cut-off circulation in the limbs of persons who may occupy the chair and thereby cause extreme discomfort. It will be readily apparent that in my improved construction the material is suspended from the side rails in such a manner that it will yield to the weight and shape of the limbs of the user and yet a sturdy construction is provided by means of the mating notched portions of side rails 10 and legs 4 and the bracing member 12.

10 It is to be understood that the invention is not limited to the precise construction set forth but that it includes whatever changes come within the scope of the appended claims.

What I claim is:—

1. In a folding chair, two pairs of pivotally connected crossed legs, bracing means connecting said pairs of legs, back rails pivotally connected respectively to the upper ends of one leg of each pair, cooperating means to support the back rails from the other legs, a seat means comprising side rails pivoted at one end to said back rails above the legs to which the back rails are connected, and mating means on the other ends of said side rails and the upper ends of said other leg of each pair arranged to hold said other ends 20 of the side rails against inward lateral movement with respect to the upper ends of said other legs.

2. A folding deck chair comprising braced pairs of pivotally connected crossed legs, a back portion pivotally mounted upon and supported by 25 said legs, side rails pivotally mounted on said back portion above the connections thereof with said legs and a seat bottom of flexible material supported on said side rails; the front portions of said rails having notched portions adapted to 30 engage correspondingly notched portions on said legs, and a cross rod bracing said legs adjacent said notched portions to prevent movement of said rails toward each other.

3. A folding chair comprising braced pairs of 35 pivotally connected crossed legs, a back portion pivotally mounted upon and supported by said legs, side rails pivotally mounted on said back portion and a seat bottom on said side rails, the ends of said legs adjacent the front ends of said 40 side rails being provided with notched portions to receive corresponding notched longitudinally grooved portions of the side rails, whereby the legs and side rails are mutually braced in a lateral direction.

55 ORVAL R. PLATTER.
